US0D1107265S

(12) **United States Design Patent** (10) **Patent No.:** **US D1,107,265 S**
(45) **Date of Patent:** **** Dec. 23, 2025**

(54) **STRUCTURAL PANEL**

(71) Applicant: **Franz Neuhofer**, Zell am Moos (AT)

(72) Inventor: **Franz Neuhofer**, Zell am Moos (AT)

(**) Term: **15 Years**

(21) Appl. No.: **29/958,556**

(22) Filed: **Aug. 20, 2024**

Related U.S. Application Data

(62) Division of application No. 35/518,139, filed on Jul. 31, 2023 (U.S. filing date under 35 U.S.C. 384), and having an international filing date of Jul. 31, 2023, now Pat. No. Des. 1,056,259.

(57) **CLAIM**

The ornamental design for a structural panel as shown and described.

DESCRIPTION

FIG. 1 is a perspective view of the structural panel, showing my new design; and,

FIG. 2 is a front view thereof.

1 Claim, 2 Drawing Sheets
